SNACK TRAY

Edwin B. Harris, Mount Carmel, Pa.

Application July 26, 1954, Serial No. 31,588

Term of patent 14 years

(Cl. D44—10)

Fig. 1

To all whom it may concern:

Be it known that I, Edwin B. Harris, a citizen of the United States, residing at Mount Carmel, in the county of Northumberland and State of Pennsylvania, have invented a new, original, and ornamental Design for a Snack Tray, of which the following is a specification, reference being had to the accompanying drawing, forming part thereof.

I claim:
The ornamental design for a snack tray, as shown.
